Ansel Hecht

United States Patent Office

ANSEL HECHT, OF NEW YORK, N. Y.

Design No. 4,525, dated December 20, 1870.

DESIGN FOR SHIRRED GOODS.

The Schedule referred to in these Letters Patent and making part of the same.

To all whom it may concern:

Be it known that I, ANSEL HECHT, of the city, county, and State of New York, have invented and produced a new and original Design for Shirred Goods or Shirt-Bosoms and other purposes, of which the following is a full, clear, and exact description, reference being had to the accompanying drawing forming part of this specification, and in which—

Figure 1 represents a face view, and

Figure 2, a transverse section of a strip or piece of shirred goods made in accordance with my design.

The puffing or shirred goods represented in the drawing are made up of one or more centrally-raised, gathered, or crinkled surfaces, A, bound on opposite sides or edges by compressed gathered or flat portions B.

Each crinkled portion, or surface A is in the form of loose gathers *b*, raised in the center longitudinally, at *c*, and presenting a fullness which has a falling to either side of said center line in reversely oblique directions and successively as regards each gather.

The flattened portions or borders B are ornamented by rows of stitching *d* ran along them in proximity to the crinkled portion A.

I claim as my invention—

The design for shirred goods, as shown.

ANSEL HECHT.
